(57) **CLAIM**

The ornamental design for a razor blade holder, as shown and described.

DESCRIPTION

FIG. 1 is a perspective view of a razor blade holder showing my new design with a blade cover attached;

FIG. 2 is a perspective view thereof without a blade cover attached;

FIG. 3 is a side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The broken line showing of the razor blade and blade cover is for illustrative purposes only and forms no part of the claimed design.
